UNITED STATES PATENT OFFICE.

STEVE GARAY, OF CLEVELAND, OHIO.

FOOT-OPERATED CUSPIDOR.

1,176,537.

Specification of Letters Patent. Patented Mar. 21, 1916.

Application filed November 30, 1915. Serial No. 64,286.

To all whom it may concern:

Be it known that I, STEVE GARAY, a subject of the King of Hungary, residing at Cleveland, in the county of Cuyahoga and State of Ohio, have invented certain new and useful Improvements in Foot-Operated Cuspidors, of which the following is a specification.

This invention relates to certain new and useful improvements in foot-operated cuspidors.

The primary object of the invention is the provision of a cuspidor that is designed in a sanitary manner, being normally closed but readily openable by the foot of the user.

A further object of the invention is the provision of a sanitary cuspidor having a foot-actuated closure and provided with a tripping means for retaining the closure in its open position whenever desired.

A still further object is to provide a cuspidor which is easy and inexpensive to manufacture but which at the same time is entirely sanitary when positioned for use in such places as offices and railway stations where the same are subject to variations in heat conditions.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—Figure 1 is a side elevation of the device partially broken away and parts being illustrated in dotted lines in their open position. Fig. 2 is a top plan view thereof. Figs. 3 and 4 are enlarged side elevations of the tripping member in its retracted and projected positions respectively, and, Fig. 5 is an end elevation thereof in its trip position.

The present form of cuspidor broadly consists of a substantially cubical casing 10 having a chamber 11 therein for the reception of a spittle container 12 furnished with an antiseptic fluid 13. The top 14 of the casing is slightly inclined toward the center thereof and is provided with a central entrance opening 15 having a tapered funnel 16 extending therefrom to a point directly above and slightly spaced from the container

12. A lid 17 is provided for the casing 10, being attached thereto by means of hinges 18, and it will be understood that the container 12 is made in the form of a drawer 60 being adapted for removal from the casing 10 by withdrawing the same therefrom by means of the handle or knob 19 positioned upon the rear end of the container 12 in a plane below the lid hinges 18. 65

An operating lever 20 is provided for actuating the lid 17 and has its forward end attached by a pivotal connection 21 to the side wall 22 of the casing 10 and adjacent the forward side of the latter. A rearwardly extending arm 23 is carried by the lid 17 adjacent the casing side 22 and is pivotally connected by means of a link 24 with the rear free end of the lever 20. A foot engaging or pedal portion 25 laterally projects from the lever 21 and is preferably provided with a roughened surface while an engagement of the lever 20 with the floor 26 acts as a stop and limits the downward movement of the lever. By this arrangement 80 it will be seen that whenever a person desires to open the cuspidor by swinging the lid 17 thereof to its open position, the foot is placed upon the pedal 25 and pressure being exerted thereon the lid is made to 85 assume the position illustrated by dotted lines in Fig. 1 by means of the operative connections between the lever 20 and the arm 23 afforded by the pivoted link 24.

It being sometimes found desirable to 90 retain the lid 17 in its open position, a latch 27 is mounted upon the casing side 22. This latch consists of a tubular barrel 28 perpendicularly projecting from the casing side 22 and provided with a bolt 29 95 slidably mounted therein and having an expansion spring 30 arranged within the barrel 28 and inwardly of the bolt 29 for urging the bolt to its projected position. A bayonet slot 31 is provided in the barrel 100 28 and through this slot an angular trip arm 32 extends, it being understood that the arm 32 is positioned within the radial portion of the slot 31 with the spring 30 held under compression when the device 105 is normally positioned inoperative and with the lid 17 closed. Upon depressing the lever 20 by means of the foot of the operator, the toe may be readily employed for shifting the trip arm 32 downwardly into 110 the longitudinal portion of the bayonet slot 31 so that the spring 30 will project the

bolt 29 above the lever 20 and thus hold the lever depressed and the lid 17 in its open position, such operative locked positions of the latch 27 and lever 20 being best illustrated in Figs. 4 and 5 of the drawings. It will be understood that the slightly sloping top 14 of the container positions the lid 17 slightly spaced therefrom which prevents any soiling of the lower surface of the lid which might occur if the lid flatly engaged the casing top 14 and this feature is designed to enhance the sanitary features of the device.

The complete operation of the device will be apparent from the above detailed description thereof, the container 12 being readily removed by means of the knob 19 whenever desired to clean the same while the lid 17 is readily opened by depressing the pedal 25 with the foot when desired to use the cuspidor, and the lid may be retained in its open position as long as desired by releasing the latch bolt 29, the latter being also readily returned to its normal retracted position by means of the trip arm 32 thereof.

While the form of the invention herein shown and described is what is believed to be the preferable embodiment thereof, it is nevertheless to be understood that various forms, modifications and arrangements of the parts may be made without departing

from the spirit and scope of the invention as claimed.

What I claim as new is:—

A cuspidor comprising a receiving casing, a top entrance opening therefor, a lid hinged to the said casing and overlying said entrance opening and slightly spaced therefrom, an exteriorly positioned arm 40 rearwardly projecting from the rear corner of the said lid and in alinement therewith, an angular extension carried by said arm and outwardly directed relative to the casing, a stub shaft carried by the casing adjacent the lower end thereof at the end of the casing opposite the hinged joint for the lid, a foot lever having a forward end pivotally connected to the said stub shaft, said foot lever being of greater length than the casing and projecting rearwardly thereof, a link pivotally connecting the end of the said arm extension and the rearwardly projecting end of the foot lever, an outwardly-projecting pedal attached to the 55 said lever, the lever being laterally positioned relative to the casing; and means carried by the casing adapted to engage the foot actuating means for holding the lid in open position.

In testimony whereof I affix my signature.

STEVE GARAY.
